UNITED STATES PATENT OFFICE.

BARNEY F. SCHMOLDT AND FREDRICK C. WALTER, OF CLEVELAND, OHIO.

WHEEL-FENDER.

SPECIFICATION forming part of Letters Patent No. 723,927, dated March 31, 1903

Application filed July 1, 1902. Serial No. 113,925. (No model.)

To all whom it may concern:

Be it known that we, BARNEY F. SCHMOLDT and FREDRICK C. WALTER, citizens of the United States, residing at Cleveland, in the county of Cuyahoga and State of Ohio, have invented certain new and useful Improvements in Wheel-Fenders; and we do hereby declare the following to be a full, clear, and exact description of the invention, such as will enable others skilled in the art to which it appertains to make and use the same, reference being had to the accompanying drawings, and to the figures of reference marked thereon, which form a part of this specification.

15 This invention relates to wheel-fenders of that class in which a forward main or tripping fender operates on contact with a person or object to drop a rear scoop or fender.

The object of the invention is to form an improved construction which will prevent mutilation or injury by the wheels of a person struck, due to the fender lifting and riding over such person, as is now frequently the case.

25 A further object is to form an improved construction by means of which the scoop will be held closer to the ground after it is tripped.

Further advantages of simplicity and construction will be apparent from the following 30 description when read in connection with the accompanying drawings in which—

Figure 1 is a side elevation of the fender. Fig. 2 is a top plan view thereof detached from the car. Figs. 3 and 4 are side elevations in different positions of a modification. Fig. 5 is a side view of another modification. Fig. 6 is a detail in section of a part of the fender shown in Fig. 5.

Referring specifically to the drawings, 6 40 indicates the frame of the car-platform. The side bars 7 of the main or tripping fender are pivoted in hangers 8, secured to the under side of the car-frame. This fender projects in advance of the car, and its forward end is 45 turned up, as at 7^a, so that it will readily ride over a person or object. The distance between the lowest point of the fender and the road-bed is small, so that a person or object of any considerable size may not pass under 50 the fender without lifting the same. The side bars 7 are extended behind the pivots, as at 7^b, forming levers to operate the scoop 9 in

the rear of the tripping-fender. This scoop is pivoted at 10 in hangers secured to the under side of the car-frame.

55

11 indicates spring-arms which are attached at one end to the side bars of the scoop 9 and project forwardly under the rear ends of the bars 7, with which they are retained in contact by bolts 12. These bolts work freely 60 in slots 11^a, formed in the spring-arms, and serve to permit a sliding contact between the arms and the side bars 7. The front of the scoop is provided with a rubber shoe 9^a to decrease shock and to prevent the scoop from 65 catching on minor obstructions or irregularities in the track.

13 is a notched bar which is pivoted to the scoop 9 and acts as a ratchet to prevent the scoop from lifting. This bar works through 70 a slot 14^a in a bracket 14, attached to the car-frame, and is held in engagement with the bracket by spring 15.

The main or tripping fender has a large 75 excess of weight forward of its pivot, and by the connection with the scoop the excess of weight normally causes the fender to take its lowest position and the scoop its highest position raised from the ground, the ratchet 13 being manipulated to allow this effect. When 80 the tripping-fender strikes a person or object, it lifts and by pressure of the rear ends of the bars 7 on the arms 11 drops or forces the scoop down until its point contacts with the road-bed, in which position the engagement of the teeth of the ratchet 13 with the bracket 14 keeps the scoop down. The arms 11 are sufficiently elastic to yield downwardly 85 and allow the tripping-fender to lift high enough to ride over the largest person or object which would ordinarily be encountered.

In the modification shown in Figs. 3 and 4 the rear ends of the bars 7 are provided with rollers 7^c, which bear upon the side bars of the scoop 9. These side bars are preferably 95 formed of channel-iron, and the rollers run in the channels. A shoulder or offset 9^b is formed by a bend in each of the bars 9, and arms 9^a project forwardly from said bars and normally rest upon the rear extensions 7^b of 100 the side bars 7, as shown in Fig. 3. In this position the excess of weight of the tripping-fender forward of its pivot lifts the scoop by pressure under the arms 9^a. When the front

end of the tripping-fender strikes and rides over a person or object, the scoop immediately falls by its weight and by the pressure and movement of the rollers 7^c on and over 5 the shoulders 9^b. In this position the spring-latch 13, pivoted to the car-frame, engages over the arms 9^a, as shown in Fig. 4, and prevents the scoop from lifting.

In the modification shown in Figs. 5 and 6 10 a yielding and operative connection between the tripping-fender and the scoop is formed by means of cylindrical casings 14, each of which is pivotally connected at its lower end to the side bar of the scoop and receives in 15 its upper end a bar or plunger 14^a, pivotally connected to the rear end of the side bar 7 of the tripping-fender. The plunger 14^a is headed, as at 14^b, to engage the shoulder 14^c in the casing to prevent withdrawal. The 20 casing contains a coiled spring 14^d in compression against the plunger 14^a. In this construction the excess of weight of the tripping-fender forward of its pivot holds up the scoop. When the fender strikes and rides 25 over a person, it drops the scoop in an obvious manner and the spring 14^d takes up any excess motion due to the size of the object or person encountered.

What we claim is—

30 1. The combination of a front fender pivotally hung from the car-frame and having extensions behind its pivot and an excess of weight in front of its pivot, of a rear scoop hung from a fixed pivot on the car-frame, and 35 a connection between the scoop and the said extensions whereby the scoop is normally lifted by said excess of weight, said connection being constructed to positively force the scoop down to the road-bed on the initial lift 40 of the fender and to yield to permit further lift thereof.

2. The combination of a front tripping-fender pivoted to the car-frame and having an excess of weight forward of its pivot, a rear 45 scoop also pivoted to the car-frame, connecting means between the fender and the scoop

operating to normally lift the scoop by said excess of weight, and to drop the scoop on initial lift of the fender, and to yield to permit further lift of the fender, and a latch engaging the scoop to hold the same down when dropped. 50

3. The combination of a front tripping-fender pivoted to the car-frame and having an excess of weight forward of its pivot, of a rear scoop pivoted to the car-frame and normally supported above the road-bed by said excess of weight, a yielding connection between the fender and scoop acting to normally support the scoop and to depress the same when the fender is lifted, and ratchet means operating between the car-frame and the scoop to hold the latter down when it is dropped. 60

4. The combination with a front fender 65 pivoted to the car-frame and having bars extending behind the pivots, of a scoop pivoted to the car-frame behind the fender, springs attached to the scoop and bearing against the said bars, whereby a yielding connection is 70 formed to depress the scoop when the fender is lifted, ratchet-bars attached to the scoop, and brackets attached to the car-frame and engaged by the ratchets when the scoop is dropped, to prevent it lifting. 75

5. The combination with a front pivoted fender having extensions behind its pivots, of a scoop pivoted behind the fender, spring-arms projecting forwardly therefrom, a slot-and-bolt connection between the said arms 80 and extensions, whereby movement of the fender is communicated to the scoop, a bracket fixed to the car-frame, and a ratchet-bar attached to the scoop and engaging the bracket to prevent lift of the scoop after drop thereof. 85

In testimony whereof we do affix our signatures in presence of two witnesses.

BARNEY F. SCHMOLDT.
FREDRICK C. WALTER.
